UNITED STATES PATENT OFFICE.

JOHN H. DUNCAN, OF OAKHILL, WEST VIRGINIA.

SPIKE OR NAIL PULLER.

SPECIFICATION forming part of Letters Patent No. 728,884, dated May 26, 1903.

Application filed October 4, 1902, Serial No. 125,902. (No model.)

To all whom it may concern:

Be it known that I, JOHN H. DUNCAN, a citizen of the United States, residing at Oakhill, in the county of Fayette and State of West Virginia, have invented new and useful Improvements in Spike or Nail Pullers, of which the following is a specification.

This invention relates to spike or nail pullers; and the object of the invention is to provide an effective device for removing nails or spikes.

Another object is to provide means whereby the fulcrum of the lever of the spike-puller can be changed to increase the leverage.

In order to appreciate the advantages of the device, reference should be had to the accompanying drawings, which illustrate its construction, and in which—

Figure 1 is a perspective view of the spike-puller constructed in accordance with my invention. Fig. 2 is a vertical longitudinal sectional view through the spike-puller.

The reference-numeral 1 designates a base, on the respective ends of which are arranged upwardly-projecting or vertical standards 2 and 3. Each standard is shaped to a step formation—that is to say, the forward portion of each standard is provided with shoulders or seats 4, arranged one above the other similar to the manner of arranging steps, so that the fulcrum of the lever for actuating the puller can be changed, as will be explained hereinafter. Arranged on the inner walls of each standard are forwardly and upwardly inclined grooves 5 and 6, which extend from near the rear of the standards to the forward edges thereof. Slidably movable in the grooves thus formed is a U-shaped clevis 7, provided with forwardly-extending ends terminating in hooked extremities 8 and 9 of the clevis 7. The clevis 7 is provided on each of its parallel arms with oppositely-disposed lugs or projections 11, which enter grooves 5 and 6, so as to retain the clevis in operative engagement with the standards of the base 1. The projections or lugs are caused to enter the grooves from the front of the standards and are secured against removal by means of set-screws 12 and 13, which enter the grooves, so that when the clevis is moved forward the lugs will abut against the set-screws and limit their movements in the grooves.

Arranged on the bar 10 are two oppositely-disposed opposing jaws 14 and 15. Each of the jaws is provided with transverse openings 16 and 17, respectively, through which the bar 10 projects. The jaws are then secured pivotally thereto by pins 18 and 19. Each jaw is segmentally shaped, and one of the jaws is provided with two upwardly-curved parallel fingers 20 and 21, while the other jaw is provided with a single upwardly-projecting curved finger 22, which is interposed between the two parallel fingers 20 and 21 to prevent a lateral movement of either of the jaws, as will be apparent by reference to Fig. 1.

Projecting from either standard is a pin or lug 23, each of which is engaged by one of the two parallel slotted arms 24 or 25, carried on the extreme ends of the fulcrum-bar 26, which is designed to rest on any one of the seats 4 of the standards 2 or 3. The slotted arms 24 and 25 tend to retain the bar 26 in its proper relative position on the seats, so as to diminish the liability of any displacement of the jaw during the operation of removing the spike.

In operating the device the proper fulcrum will be determined after placing the jaws 14 or 15 in engagement with the spike, and a pinch-bar of any preferred construction, such as is designated by the reference-numeral 27, will be inserted between the fingers 20 and 21 on one of the jaws and the finger 22 on the other, so that the pinch bar or handle will rest upon the fulcrum-bar 26, and by applying pressure to the opposite end of the bar the spike can be promptly removed. The clevis 7 will materially assist in guiding the jaws when pressure is applied to the ends 8 and 9, forming efficient bearing for the reception of the ends of the bar 10. Thus an effective and durable spike-puller is provided, which is particularly adapted for use in removing spikes on railways and similar places.

Having thus described the invention, what is claimed as new is—

1. A spike-puller, comprising a pair of standards arranged parallel with each other and provided with slots on their inner sides, of a clevis slidably secured in said slots and having bearings in the side arms thereof, a pivoted bar resting in the bearings, pivoted jaws carried by the pivoted bar, a fulcrum-

bar on the standards, and a handle adapted to rest upon the fulcrum-bar and engage the under side of the jaws whereby the spike can be released.

5 2. A spike-puller, comprising a pair of standards provided with inclined slots, of a clevis movably secured in said slots, a pair of opposing jaws carried by the clevis and a fulcrum-bar supported by the standards, and 10 a lever adapted to engage the jaws to close them on the spike and extract it.

3. A spike-puller comprising a pair of parallel standards having seats of varying heights, lugs projected oppositely from the standards, a fulcrum-bar having slotted depending ends engaging the lugs, said bar being adapted to be seated on the different 15 seats, pivoted jaws secured to the standards,

and a bar or lever adapted to rest upon the fulcrum and force the jaws upward. 20

4. A spike-extractor comprising a base, a pivoted clevis carried thereby, a pair of opposing pivoted jaws carried by the clevis, one of said jaws having parallel fingers, the other jaw having a single finger interposed 25 between the parallel fingers, a fulcrum-bar carried by the base, and a lever for engaging the under sides of the jaws whereby they can be forced upward to extract the spike.

In testimony whereof I affix my signature 30 in presence of two witnesses.

JOHN H. DUNCAN.
